(57) **CLAIM**

The ornamental design for an arthropod trap, as shown and described.

DESCRIPTION

FIG. 1 is an upper-front-right perspective view of an arthropod trap, according to our new design;

FIG. 2 is a top plan view of the arthropod trap shown in FIG. 1;

FIG. 3 is a bottom plan view of the arthropod trap shown in FIG. 1;

FIG. 4 is a front view of the arthropod trap shown in FIG. 1;

FIG. 5 is a rear view of the arthropod trap shown in FIG. 1;

FIG. 6 is a left side view of the arthropod trap shown in FIG. 1;

FIG. 7 is a right side view of the arthropod trap shown in FIG. 1; and

FIG. 8 is an upper-front-right perspective view of the arthropod trap shown in FIG. 1, showing the arthropod trap in an open configuration;

FIG. 9 is an upper-front-right perspective view of an arthropod trap, according to a second embodiment of our new design;

FIG. 10 is a top plan view of the arthropod trap shown in FIG. 9;

FIG. 11 is a bottom plan view of the arthropod trap shown in FIG. 9;

FIG. 12 is a front view of the arthropod trap shown in FIG. 9;

FIG. 13 is a rear view of the arthropod trap shown in FIG. 9;

FIG. 14 is a left side view of the arthropod trap shown in FIG. 9;
